TREATMENT OF HYDROCARBON OILS

Richard F. Davis, Chicago, Ill., assignor to Universal Oil Products Company, Chicago, Ill., a corporation of South Dakota

Application December 11, 1931, Serial No. 580,379

5 Claims. (Cl. 196—36)

This invention relates to the treatment of hydrocarbon oils and while not limited thereto refers more particularly to the treatment of low boiling cracked distillates.

5 More specifically the invention relates to the treatment of hydrocarbon oils by chemical means to improve their quality as regards their content of unsaturated hydrocarbons and sulphur compounds, a method of treatment being disclosed which offers distinct advantages over the methods commonly in use in the art for effecting such results.

10 The selective removal of the more highly unsaturated hydrocarbons and the sulphur compounds from petroleum oils whether of a straight run or a cracked character, is necessitated by the fact that excessive amounts of the former class of compounds render the oils unstable as to color and their tendency to deposit gums and resinous 15 materials and the tendency of the sulphur compounds to impart offensive odor to the products and corrode equipment in which they are used. In the case of hydrocarbon mixtures boiling within the range of commercial motor fuel the presence of excessive amounts of gum-forming constituents renders the fuel unstable because of the tendency of the deposited gums to clog feed lines, carburetors, valves, etc., and the presence of sulphur above a certain amount is especially 20 objectionable from the fact that oxides of sulphur are formed in the burning of fuel and cause corrosion in the crank case.

25 Sulphuric acid treatment is employed almost universally to reduce the unsaturation and sulphur content of petroleum fractions. The principal disadvantage of this method of treatment lies in the fact that it is difficult to control its tendency to oxidize, and limit its action to direct combinations with undesirable constituents to produce sludges from which the acid is readily 30 regenerated by hydrolysis. It frequently occurs when acid treatment is conducted to a point necessary for the reduction of sulphur content to a certain point that excessive amounts of acid 35 must be used which remove desirable components of the oils such as mono olefins and certain ring compounds along with the sulphur. The present invention is concerned with a method of treatment whereby the necessity for the use of sulphuric acid in treating hydrocarbon oils is substantially if not completely eliminated, treating reactions being substituted which may be controlled to be more definitely selective and which may be applied under a wider range of conditions.

40 45 50 55 In one specific embodiment the invention com-

prises treating hydrocarbon oils either in liquid or vapor phase with sulphur dioxide gas in the presence of aluminum chloride.

The reactions characteristic of this method of treatment have been found to produce effects 5 substantially equivalent to those produced by the use of sulphuric acid, without the tendency to oxidize the materials under treatment with the production of tarry polymers and sludges from which it is difficult to regenerate the sulphuric 10 acid. The reactions of sulphur dioxide in the presence of aluminum chloride upon unsaturated straight chain compounds produce compounds of the nature of alkyl sulphites and in the case of ring compounds of compounds typified by the 15 sulphuric acids analogous in structure to the well known sulphuric acids but having one less oxygen atom. From sludges containing such compounds the treating reagents are regenerated with comparative ease, by regulated heating since the compounds formed are more or less loose addition compounds and altogether the process may be considered as substantially cyclic.

To illustrate some of the applications of the method of treatment comprised within the invention the attached drawings have been provided which represent diagrammatically in side elevation two arrangements of apparatus which may be employed in conducting treatments. Figure 1 shows in essential detail an arrangement of equipment comprising a cracking unit with fractionating and treating equipment following and Figure 2 indicates an arrangement which may be employed to treat hydrocarbon oils in substantially liquid phase or while they are undergoing distillation 30 and fractionation.

35 Referring to Fig. 1, raw oil may be supplied to a cracking unit from a line 1 controlled by a valve 2 to a charging pump 3 which may discharge into line 4 controlled by a valve 5, line 4 having branch line 6 controlled by a valve 7. The portion of the charging oil discharged through valve 5 may enter a fractionator 21 at some point best suited to properly assist in the fractionation of cracked products by its cooling effect, be preheated and be discharged with reflux condensates through a line 8 controlled by a valve 9. A portion of the raw oil may be discharged through a line 6 controlled by a valve 7 branching from line 4 and combine with the heated oil in line 8 to enter a line 11 leading to a combined feed pump 10. This pump may discharge through a line 10' controlled by a valve 11' into a continuous tubular heating element 14 disposed to receive heat from a suitable 40 45 50 55 60 65 70 75 80 85 90 95 100 105 furnace 15 wherein the combined feed is heated to temperatures necessary for cracking reactions, the heated products passing through a line 16 controlled by a valve 17 to an enlarged zone 5 typified by reaction chamber 13 in which the conversion reactions are allowed to proceed without further application of heat, though heat may be conserved by properly insulating the chamber. Such a chamber may be provided with upper and lower removable manheads 17' and 17'' respectively to permit access to the chamber for cleaning out coke deposits and a liquid draw line 19 controlled by a valve 20' for the continuous or intermittent removal of nonvaporized liquids. 10 Temperatures and pressures employed during the cracking period will vary generally with the nature of the oil cracked and the results desired though it may be stated that for most commercial purposes cracking temperatures are included within the range of 800 to 1000° F. and pressures between 50 and 500 pounds per square inch. 15

Vapors from the reaction chamber may pass through a line 19 controlled by a valve 20 and 25 into a preliminary fractionator or dephlegmator 21 which has been already mentioned. Vapors from such a fractionator may pass through a line 22 controlled by a valve 23 to a secondary fractionator represented by 24 in the drawings, 30 of a design and type suitable for the production of overhead fractions of approximate gasoline boiling point range. Such a fractionator may be, for example, of the so-called bubble tray type employed in many distilling processes. To assist 35 in maintaining the proper boiling point range of the vapors issuing from the top of this secondary fractionator, a portion of the vapors necessary for recirculation to the top of the tower may be diverted through a line 25 controlled by a valve 26 40 and pass through an auxiliary condenser 27 from which the cooled products pass through a line 28 controlled by a valve 29 to a receiver 30. Such a receiver may have a line 30' controlled by a valve 34' for the transfer of distillate to a pump 33 45 which discharges into a line 34 controlled by a valve 35 back to a point near the top of a fractionator. The admission of vapors to line 25 may be conveniently regulated by the controlled automatic withdrawal of gases from receiver 30 50 through a line 31 controlled by a valve 32.

The portions of the vapors from the secondary fractionator not necessary for use as reflux may pass through a main vapor line 36 which has interposed therein a valve 36'. Such vapors 55 which represent approximately the cracked products of gasoline boiling point range may be effectively treated at this point prior to their condensation by the method characteristic of the present invention, thus eliminating at once the 60 use of sulphuric acid and the necessity for re-running of the condensed product. To this end regulated mixtures of sulphur dioxide gas and aluminum chloride vapors may be admitted to the vapor line at a point A from a line 37 controlled 65 by a valve 38. Such vapors mixtures may be produced in a generator 39 which has a line 42 controlled by a valve 43 for the admission of sulphur dioxide gas, a line 40 controlled by a valve 41 for the introduction of substantially anhydrous 70 aluminum chloride either as a solid or a vapor since aluminum chloride sublimes without going into the liquid phase under ordinary pressures. Generator 39 may be externally heated if necessary to produce ready volatilization of aluminum chloride and insure the generation of properly pro-

portioned mixtures with sulphur dioxide which are then passed into line 37. The oil vapors and treated materials may then be passed into a reaction chamber and separator 44 in which the treating reactions are completed and the sludge 5 separated, the latter being withdrawn continuously or intermittently through a line 45 controlled by a valve 46. It may be advantageous under certain circumstances to add additional amounts of the sulphur dioxide-aluminum chloride vapor mixture to the treating chamber and to permit this, a line 37' controlled by a valve 38' may be provided connecting line 37 directly with reaction chamber 44. The treated vapors from the reaction chamber may pass through a line 47 10 controlled by a valve 48 and have such vaporous acidic constituents as may result from the preceding treatment neutralized by alkaline gases such as ammonia or aqueous solutions such as caustic soda introduced from a line 49 controlled 15 by a valve 50 at a point B, additional amounts of neutralizing reagents being added to the separator 51 through a branch line 49' controlled by a valve 50' if found necessary. Separator 51 may be provided with a draw line 52 controlled 20 by a valve 53 for the removal of liquid or solid accumulations. 25

Neutralized oil vapors emerging from separator 51 may pass through a line 54 controlled by a valve 55 and enter a chamber 56 containing 30 filtering material such as fuller's earth, sand, finely divided clays, etc., for the removal of treating reaction products. A line 57 controlled by a valve 58 may be provided to admit steam or other gases at a point C in line 54 or into the top of 35 the filter chamber from a branch line 54' controlled by a valve 55' to control the rate of passage of the vapors through the stationary filter mass or at times to wash the same free from adhering impurities. 40

Treated vapors, after passing the filter bed, may be conducted through a line 59 controlled by a valve 60 to a final fractionator 61 capable of producing treated end product vapors and simultaneously removing heavy portions which may 45 have resulted from polymerization reactions in the preceding treating zones. The vapors from such a fractionator may pass through a line 69 controlled by a valve 70 and be cooled in a condenser 71, the cooled products passing through 50 a line 72 controlled by a valve 73 and entering a receiver 74 provided with a line 75 controlled by a valve 76 for the release of gas and a line 77 controlled by a valve 78 for the removal of treated gasoline to storage. As previously described 55 in connection with the secondary tower of the cracking unit, a portion of the treated gasoline may be returned to the top of fractionator 61 for controlling the boiling point range, such portions being transferred to a pump 81 through a line 60 79 controlled by a valve 82 and discharged through a line 83 controlled by a valve 83.

Bottoms from fractionator 61 may pass through a line 66 controlled by a valve 66 to a receiver 64 which also receives bottom liquids from filter chamber 56 through a line 62 controlled by a valve 63. To prevent vapor lock, line 67 controlled by a valve 68 may be provided connecting the vapor space of receiver 64 with the fractionator 61. Fractions boiling above the desired 70 range in the finished gasoline may be returned to the secondary tower of the cracking system by means of a pump 86 which withdraws such fractions from receiver 64 through a line 84 and a 75

valve 85 and discharges them into a line 87 controlled by a valve 88.

The preceding description was concerned with a method of treating cracked vapors of approximate gasoline boiling point range with the reactions characteristic of the invention prior to their final rectification.

In Figure 2 an apparatus capable of effecting treatments in substantially liquid phase is shown which consists of a treater 115, a heating element 107 disposed to receive heat from a furnace 108, a condenser 133 which may return a portion or all of the condensed liquids to the treater and means for admitting the treating reagents, 15 circulating the liquids being treated and disposing of reaction products.

Line 101 controlled by valve 102 indicates a line through which hydrocarbon liquids to be treated may be introduced into a line 103 on the suction 20 side of pump 104 which discharges into a line 105 controlled by a valve 106 leading to heating element 107 or into branch line 109 controlled by valve 110 which by-passes the heating element. Line 109 makes a junction with line 111 at the 25 exit of the heating element and either heated or cold liquids may be added to the treater by the use of valve 112 in this line or through a branch line 113 controlled by a valve 114 which typifies a line provided at some level below the top of 30 the treater.

Treater 115 may be of any type suitable to the purposes of the treatment such as a cone-bottomed agitator preferably gas-tight or a fractionating column of some variety. A manhead 35 116' may be provided to permit entry to the treater and line 129 controlled by a valve 130 may be provided for the admission of treating agents characteristic of the invention. Line 116 controlled by valves 117 and 118 is shown leading 40 from the bottom of the cone of the treater and may be utilized to withdraw residual accumulations for ultimate disposal or for the circulation of only partially spent reagents, in which case valve 121 may be opened and valve 118 closed 45 and the materials returned through line 103 to the circulating pump 104. In operations involving the continuous removal of sludge and at the same time circulation of the oil undergoing treatment, a line 119 controlled by a valve 120 may be 50 provided which takes suction on the treater at a point above the level of the sludge and leads to line 103. To permit the admission of sulphur dioxide to the suction side of the circulating pump a line 122 controlled by a valve 123 may be provided 55 and for the introduction of aluminum chloride in a concentrate or slurry in more or less non-reactive suspension mediums, a line 124 controlled by a valve 125 may lead to a pump 126 which discharges such suspensions to a line 127 controlled 60 by a valve 128 into circulating line 119 leading ultimately to the suction side of the circulating pump.

The equipment thus far described may be utilized in a variety of ways, the oils being treated 65 either cold or at suitable superatmospheric temperatures. For example, cold oil may be charged to the treater, finely divided anhydrous aluminum chloride added through the manhead 116' or by means of pump 126 and treatments conducted 70 by merely introducing sulphur dioxide from line 129, suitable distributing means being employed to effect good contact and the introduction of the gas serving to maintain the chloride in suspension. In such an event evolved gases may be 75 discharged through the vapor line 131 from the

top of the treater and pass through a valve 132 in this line for suitable disposal. In other cases where the optimum temperature of treatment is above atmospheric, the contents of the agitator or treater may be gradually brought to the desired 5 temperature by circulating through heating element 107, the reagents being added gradually to produce the desired treatment and the sludge drawn at the completion of the treatment. Such a treatment may be conducted under superatmospheric pressure necessary to prevent substantial volatilization of the oils undergoing treatment or under substantially atmospheric pressure with refluxing of the volatilized constituents. In such a case the lighter and more 15 volatile portions may pass through a condenser coil 133 which has an outlet line 134 controlled by a valve 135 and a branch line 141 controlled by a valve 142 leading back to the treater.

Continuous treatment may be conducted by 20 utilizing the treater as a fractionating column in which case the oil to be treated and the treating reagents are added continuously, the combined fractionator and treater producing end product vapors which are collected in receiver 136 and 25 sludge and heavy liquids which are drawn from the system through line 116 by the manipulation of valves 117 and 118. Receiver 136 may be provided with line 137 controlled by a valve 138 for the release of gas accumulations and line 139 30 controlled by valve 140 for the removal of treated liquids.

While the treatment characteristic of the invention may be used advantageously in many instances without any other type of treatment, it 35 is intended to include in the invention the use of this treatment in conjunction with other commonly known methods of treatment such as treatments with sulphuric acid of varying strength, caustic soda, fuller's earth and other polymerizing 40 reagents. Notable effects may be observed when other volatile metallic halides, for example, stannic chloride, boron fluoride, etc., are substituted for aluminum chloride uniformly mentioned in the description. 45

As an example of results obtainable by a vapor phase treatment comprised within the scope of the invention, the case of cracked vapors from a unit running on 24 gravity fuel oil may be mentioned. These vapors may be treated according 50 to the method described in connection with Figure 1 by sulphur dioxide gas at the rate of 2½ pounds per barrel of the treated gasoline produced, there being used also aluminum chloride at the rate of approximately 1½ pounds per bar- 55 rel. The finished gasoline produced by this treatment at the temperature of the vapors from the secondary fractionator (which may be in the neighborhood of 375° F.) may possess all the characteristics required in commercial motor fuel, 60 to wit, a color of over 25 on the Saybolt scale, gum content of less than 25 mgs. as determined by the copper dish method and a sulphur content of approximately 0.1%.

As an example of a liquid phase treatment, a 65 kerosene distillate from a California crude may be treated at a slightly elevated temperature, for example, 150° F. in an apparatus similar to that described in connection with Figure 2. Finely divided aluminum chloride at the rate of approx- 70 imately 2 pounds per barrel of oil treated may be added to the oil in the agitator and sulphur dioxide introduced during circulation of the oil and chloride at the rate of 10 pounds per barrel. The distillate prior to such a treatment may have 75

a Bé. gravity of 38 and possess objectionable color and odor in addition to having very poor burning qualities in the customary lamp tests. By treatment to exhaustion of the reagents used in the amounts mentioned such a distillate may be brought to practically water white color with a raise in gravity to 40° Bé. with sufficient increase in burning properties to render the oil saleable as a commercial kerosene.

10 While the foregoing descriptions and examples have served to indicate to a certain extent some applications of the process of the invention, it is to be understood that they are given for illustrative purposes only and are not to constitute a limitation upon the generally broad scope of the invention.

I claim as my invention:

1. In the refining of hydrocarbon distillates containing unsaturated hydrocarbons and sulphur compounds, the step which comprises treating the distillate with sulphur dioxide in the presence of aluminum chloride.

2. In the refining of normally liquid hydrocarbon distillates containing unsaturated hydrocarbons and sulphur compounds, the step which comprises treating the distillate in vapor phase with a mixture of sulphur dioxide gas and a metallic 5 halide catalyst which is vaporized at the temperature of the hydrocarbon vapors.

3. In the refining of hydrocarbon distillates containing unsaturated hydrocarbons and sulphur compounds, the step which comprises treating 10 the distillate in vapor phase with a mixture of sulphur dioxide gas and aluminum chloride vapors.

4. A process for refining cracked gasoline which comprises contacting the same with sulphur dioxide gas in the presence of aluminum chloride.

5. A process for refining cracked hydrocarbon vapors of motor fuel boiling range which comprises contacting the vapors with sulphur dioxide gas in the presence of aluminum chloride 20 vapors.

RICHARD F. DAVIS.
